SPONGE MOP

Edward D. Zelinski, Worth, and Stanley Stomiany, Hazel Crest, Ill., assignors to The Drackett Company, a corporation of Ohio

Filed Feb. 20, 1963, Ser. No. 259,831

1 Claim. (Cl. 15—244)

This invention relates to sponge mops comprising a support element and a replaceable sponge element attached thereto. More particularly, the invention embraces mops of the above type wherein the sponge element is free to move laterally, permitting expansion and contraction of the sponge block upon wetting and drying. The sponge element is attached to the mop element by means of a slot and tab arrangement and is not fixedly secured to the backing member at any point.

In the prior art, mops of the above type are generally constructed with the sponge element fixedly secured to the support element by means of screws and wing bolts. In construction, the sponge element comprises a sponge block secured to a metal plate which extends substantially from one end to the other of the sponge block and is fixedly secured by means of cement or other suitable adhesive. The metal plate contains screws which are engaged in holes in the backing plate of a support element and fixedly secured thereto by means of wing bolts. As is apparent, there is no freedom of movement of the sponge element in relation to the support element.

Although such mops have been enthusiastically received by the housewife in preference to the more conventional string type mop, one problem encountered with such mops is the contraction of the sponge block upon drying, causing the backing plate to warp unless the backing plate is constructed from relatively heavy metals. However, if a heavy metal backing plate is employed, in addition to increasing the cost of the assembly, the sponge block has a tendency to tear at its points of attachment to the backing plate upon drying, due to shrinkage. Moreover, attachment of the sponge element to the support element by means of screws and wing bolts is relatively expensive and invariably requires tools for replacement since, oftentimes, the screw threads become damaged or rusty upon contacting water, causing difficulty of removal.

As a partial solution to the problem of contraction of the sponge element and consequent damage to the backing plate or the sponge block, Richards et al. U.S. Patent No. 2,663,042 suggests a self-adjusting mop head which permits the sponge block to expand and contract freely. The patentee proposes the construction of a mopping element comprising an absorbent pad which is secured to slide plates covering less than the entire area of the absorbent pad. The slide plates are fixedly attached to the backing plate of the mop at least at one point, but again at less than the entire area of the backing plate. The absorbent pad is fastened at additional points to the backing plate through slotted openings in the plate by means of a screw and wing bolt type arrangement. The slots permit lateral movement of the absorbent pad to compensate for shrinkage and expansion during use.

Although the Richards et al. patent, in some respects, is a step ahead, it is not completely practical and has not been adopted by the art as is apparent from later issued patents and failure of the product to be marketed, despite

2

the passage of a number of years. The structure is expensive to construct containing only one less component than the earlier mops and, additionally, requires an intermediate slide plate which is fixedly secured to the backing plate. As is apparent, the difficulty of disengaging and replacing the sponge element is increased. Moreover, by using a modified screw and wing bolt arrangement, there is a possibility that the slotted opening will become fouled due to dirt or rust, substantially reducing the freedom of lateral movement which is desired.

Accordingly, it is an object of the instant invention to provide an improved mop design wherein the sponge element is not fixedly secured to the mop element at any point, permitting lateral movement of the sponge, but which still holds the sponge element in proper alignment during operation.

It is another object of the invention to provide a mop of the above-described type which possesses a minimum number of components, permitting low cost and simplified construction.

It is another object of the invention to provide a mop of the above-described type eliminating projecting points or fasteners, permitting more convenient and attractive packaging.

It is still a further object of the instant invention to provide a mop of the above-described type which eliminates screw and wing bolt assembly, precluding the possibility of stripping of threads or rusting of the threaded portions.

It is still another object of the invention to provide a mop of the above-described type which permits the attachment of the sponge element without use of screws and wing bolts, permitting quick interchangeability of sponge elements without need of tools.

These and other objects will become more fully apparent from the following detailed description with particular emphasis being placed upon the drawings.

In general, the objects of the instant invention are accomplished by constructing a mop employing a sponge element comprising adaptor plates fixedly attached by suitable means to a sponge block. The adaptor plates have a slot for receiving a tab which preferably is formed integrally with the backing plate of the support element. By employing the design of the present invention, the sponge block is held firmly permitting mopping, waxing or similar household operations, but still allows freedom of lateral movement to compensate for expansion and contraction. The design permits a minimum number of parts, providing for rapid replacement of the sponge element without need of tools.

In the accompanying drawing, forming a material part of this application and in which like numerals are employed to designate like parts throughout the specification:

FIGURE 1 is an exploded perspective view of a mop assembly in accordance with the present invention with the mop handle being illustrated fragmentarily in broken lines;

FIGURE 2 is an exploded fragmentary perspective view of the sponge element of the mop assembly in accordance with the present invention;

FIGURE 3 is a section through the assembled mop structure taken on a plane designated by the line 3—3 in FIGURE 1 showing the mode of attachment of the sponge element onto the support element of the mop; and

FIGURE 4 is a fragmentary exploded perspective view of a modified mop assembly.

More specifically, referring to FIGURE 1 of the drawing, 1 defines the sponge element and 2 defines the support element. The sponge element, shown more in detail in FIGURE 2, is composed of sponge block 10, adaptor plates 11, and fabric 12. In construction, each adaptor plate 11 is firmly fastened by adhesive or other suitable means to sponge block 10 and thereafter fabric 12 is firmly anchored to sponge block 10, superimposed on adaptor plates 11. The support element 2 is composed of backing plate 21, optionally presser element 22 and socket 23 which receives a handle shown fragmentarily in broken lines. Since components of the support element, other than the backing plate, are not critical to the instant invention, only the backing plate will be considered in detail.

Each adaptor plate 11, as seen most clearly in FIGURES 1 and 4, comprises a metal plate which is firmly anchored to sponge block 10. Each plate has slot 13 which preferably is constructed integrally with the plate defined by raised portions 14. Advantageously, the leading edge of the raised portions 14 are rounded or tapered to facilitate engagement of the slot with tabs 24 which are preferably formed integrally with backing plate 21. In construction, the tabs 24 can be stamped from backing plate 21 in a single operation, forming an integral unit.

Sponge element 1 is attached to support element 2 as shown in FIGURE 3. Thus, the sponge element is fastened by engaging first slot 13 with tab 24 on one end of the backing plate and thereafter the sponge block is bent or flexed for engagement of the second slot and tab. In FIGURE 3, the backing plate is formed with a depressed marginal flange 26 surrounding the relatively raised main body of the plate and connected thereto by a depending marginal shoulder 25, portions of which are in longitudinal alignment with the slide means or tabs 24 at the relatively remote or outer ends thereof to function as stops for limiting the lateral outward movement of the slide means 13 carried by the adapter plates 11.

This feature eliminates the possibility that the sponge element will become disengaged during operation and allows only the desired amount of free lateral movement. It may be necessary to wet the sponge element to obtain the necessary flexibility for attachment to the support element.

It will be readily apparent that the raised portions 14—14 of each adapter plate constitute oppositely laterally projecting ledges of a slide means, these ledges being spaced above and parallel to the flat upper surface of the pad 10 for reception on and longitudinal sliding movement along the respective ledges defined by the opposite laterally projecting edges of each tab 24. The tabs 24 thus also function as slide ways or slide means on the backing plate 21 whereby to replaceably support the pad or sponge 10 from the mop. Obviously, in order to assemble the pad 10 to the backing plate 21 the flexible mid-portion of the pad 10 between the relatively longitudinally spaced adapter plates 11—11 is flexed downwardly or away from the backing plate while the opposite ends of the pad 10 bearing the respective slide means 14 are compressed toward each other to be brought into alignment with the respective adjacent inner ends of the slide ways 24 of the backing plate. Upon inserting these slide means 13—13 onto the slide ways 24—24 respectively, and straightening out the pad 10 to permit relative longitudinal expansion thereof, the slide means 13 are relatively urged apart for supporting reception by the slide ways 24—24. Longitudinal movement or displacement of the pad 10 after thus being assembled to the backing plate is prevented, except to an immaterial extent, by abutment of one of the slide means 13 with a relatively aligned portion of the shoulder 25 which, as above mentioned, acts as a stop.

As a modification of the device shown in FIGURE 1,

the adaptor plate 11 can be provided with a punched helical impression 16, as shown in FIGURE 4, to receive screw 28 which passes through opening 29 on the backing plate to anchor the sponge element to the support element. As is apparent, this modified structure does not possess the freedom of lateral movement of the design according to the instant invention, however, it permits the utilization of sponge element 1 in the prior art mops, as shown in U.S. Patent No. 3,014,230, which may still be in service.

As is apparent, the present type of construction, in addition to allowing for lateral movement compensating for expansion and shrinking due to wetting and drying of the sponge, permits the housewife to attach and detach the sponge element to and from the metal head of the mop without need of tools. Thus, the sponge element can be slipped on or off quickly, permitting the use of more than one sponge element on the same support element for different operations. For example, the housewife can use one sponge element for washing floors and, thereafter, replace the element with a second sponge element and use the assembly for waxing without loosening numerous screws. The quick interchangeability of sponge elements is a desired advantage. Moreover, since the construction enables the use of a minimum number of parts, with the parts preferably being stamped from, and forming an integral part of the backing and adaptor plates, a substantial reduction in manufacturing costs is obtained.

As a further feature, the support element possesses a clean line, eliminating projections from the structure as in the case of a support element using wing bolts and screw heads, thereby lessening the possibility of marring or damaging surfaces when the mop accidentally bumps furniture or is used under low furniture. Elimination of projecting points or fasteners also permits more convenient packaging inasmuch as the upper surface of the sponge element will be much flatter, allowing better and more compact packaging in shipping cartons. As is apparent, the possibility of tearing the wrapping material is reduced, providing a better appearance at the point of purchase. Finally, the slot arrangement, together with positioning of the sponge attachment plates during manufacturing assembly, gives more complete control in alignment of the sponge element with the support element. These are only some of the features which are inherent in the described structures.

It should be appreciated that while various embodiments of this invention have been described, the invention is not restricted thereto. Modifications will be apparent to one skilled in the art and which come within the scope of the appended claim.

What is claimed is:

A mop comprising an elongated flexible absorbent pad having a normally flat upper surface co-extensive in length therewith, rigid adapter plates affixed on said surface in relatively longitudinally spaced relation, a rigid elongated backing plate having a pair of relatively longitudinally spaced and aligned slide means carried thereby adjacent the opposite ends of said plate, each said slide means comprising laterally projecting ledges spaced below and in a common plane parallel to the plate, means on said backing plate defining stops adjacent the relatively remote outer ends of said slide means and in longitudinal alignment therewith, a pair of similarly spaced slide means affixed to the respective adapter plates, each such last-mentioned slide means including laterally projecting ledges in a common plane spaced above and parallel to the said surface of the pad and longitudinally slidably supported beneath said backing plate on the respective ledges of said first-mentioned slide means, the mid-portion of said pad between said adapter plates being free for flexing toward and away from said backing plate whereby to permit withdrawal of the last-mentioned slide means through the relatively adjacent inner ends of said first-mentioned slide

means, said slide means of both the adapter plates and the backing plate being formed integrally with said plates by tabs struck out from the respective plates, said ledges of one pair of slide means being laterally outwardly directed, and said ledges of the other said pair of slide means being laterally inwardly directed.
